UNITED STATES PATENT OFFICE.

THOMAS MIDGLEY, OF SPRINGFIELD, MASSACHUSETTS, ASSIGNOR TO THE FISK RUBBER COMPANY, OF CHICOPEE FALLS, MASSACHUSETTS, A CORPORATION OF MASSACHUSETTS.

METHOD AND MACHINE FOR PRODUCING CORD FABRIC.

Application filed April 17, 1919. Serial No. 290,760.

To all whom it may concern:

Be it known that I, THOMAS MIDGLEY, a citizen of the United States of America, residing at Springfield, in the county of 5 Hampden and State of Massachusetts, have invented certain new and useful Improvements in Methods and Machines for Producing Cord Fabric, of which the following is a specification.

10 My present invention relates to a method and a machine for coating fibrous material with rubber, and in particular for producing what is commonly known as cord fabric, which is a weftless fabric used in the construction of rubber tires, and which is composed of a plurality of parallel cords united by a matrix of rubber.

15 It has for its object the manufacture of a fabric having the fibrous material thereof 20 united more firmly to the rubber than has formerly been the case. A further object is the provision of a method and a machine for increasing the speed with which cord fabric may be manufactured. Further objects will appear from the specification and claims.

25 It is a well known fact in the manufacture of compound rubber and fabric goods, that great difficulty is experienced in securing 30 a firm bond between the fabric and the rubber. The fabric is not, as it were, wet by the rubber, and the latter does not penetrate beyond the outermost fibers of the fabric-forming material. Considerable effort has 35 been directed towards finding some way in which the adhesion between the rubber and the fibrous material could be improved and by which the rubber could be made to more deeply penetrate into the fibrous material. 40 These efforts have been, on the whole, unsuccessful. The rubber cannot be worked or kneaded into the fibrous material, as its action seems to be merely a mechanical catching of the outermost fibers, and as it does not 45 wet the fabric under any pressure which can be brought to bear.

50 In a co-pending application filed by me March 18, 1919, Serial No. 283,368, I have described one way in which this adhesion of the fabric and rubber may be improved and by which a satisfactory cord fabric may be produced. The present invention is directed towards the same result but in a different direction.

It has also been proposed to make a 55 slightly different type of cord fabric by first forming what is known as thread fabric, having the warp formed of cords and the weft formed of threads rather widely spaced, as, for example, every half inch; and then 60 running this fabric through an ordinary form of calender such as is used for coating woven fabric. One difficulty with this process is that the cords are necessarily located close together, so that the rubber does not 65 flow between the cords and occurs only as a thin flat coating touching the cords over but a slight portion of their circumference. This method, of course, does nothing towards 70 solving the problem of imperfect adhesion referred to above. By my invention, I insure that the rubber will not only firmly adhere to the fibers of the cords, but will also penetrate the spaces between the cords so 75 that the cords themselves will be entirely enclosed by rubber. Of course a fabric having the cords actually touching each other can be produced if desired, but in this case the rubber will not penetrate between the cords and the bond between the cords and 80 rubber will not be as firm as where the cords are slightly spaced.

I have found that by first moistening the 85 fabric or cords with some liquid which acts as a solvent of rubber, the rubber later applied thereto will penetrate into the fibrous material, and will be firmly bonded thereto. Any of the usual rubber solvents, such as gasoline, naptha, carbon disulphide, or benzol, may be used, but I prefer to use a solvent comprising benzol with from one to ten 90 per cent of resin added. After having received this preliminary moistening, the fibrous material is pressed in any suitable manner into contact with a thin sheet of 95 rubber which permeates the fibrous material as described above. The improvement in adhesion between the fibrous material and the rubber is present whether ordinary fabric is being coated or cord fabric is being made. 100 My invention, is however, especially suited for the manufacture of cord fabric, and the mechanism I prefer for carrying out the invention has been illustrated in connection with such manufacture.

105 The mechanism for moistening the cords, where cord fabric is being made, and for applying the rubber thereto may be of any de-

sired type but I have shown, as the preferred embodiment, my invention as applied to a calender such as is now in use for coating ordinary woven fabric. This machine will 5 be described with particular reference to the accompanying drawings, in which—

Fig. 1 represents a fragmentary vertical section through a calender, embodying my invention, a creel for supplying the cords 10 being shown diagrammatically;

Fig. 2 is a fragmentary elevation of parts shown in Fig. 1;

Fig. 3 is an enlarged detail of the supports 15 for the comb, also showing the roll for pressing the cords into contact with the rubber;

Fig. 4 is a transverse section of a compound sheet made by the apparatus above;

Fig. 5 is a diagrammatic view showing 20 one manner of forming a cord fabric coated on both sides; and

Fig. 6 is a transverse section of such a fabric.

My invention has been illustrated as applied to a calender of an ordinary type having 25 side frames 10 and upper and lower rolls 11 and 12 respectively. These may be two of the rolls of an ordinary three roll calender, the other roll being spaced from the two being used so as to be inoperative; and for all 30 practical purposes, the calender may be treated as if it had but two rolls. These rolls are rotated in the direction of the arrows by any suitable mechanism which is not necessary to illustrate as such devices are well 35 known. A bank of rubber 13 is placed between and to one side of the rolls 11 and 12, and is worked by these rolls into a thin sheet 14 in which form it is delivered to the cord applying device.

40 The cord moistening, spacing and applying mechanism is mounted on a shelf 15 secured in brackets 16 fastened to the frames 10 of the calender. Slides 17 are mounted on ways 18 carried by the shelf and are threaded to receive screws 19 which rotate freely in brackets 20 fastened to the shelf 15, but are confined against axial motion therein. Screws 19 carry worm wheels 21 meshing with worms 22 on a shaft extending 45 between brackets 20 and rotatable by means of a hand wheel 23. By turning this hand wheel, slides 17 and the parts carried thereby may be reciprocated toward and away from the calender roll for a purpose to be described. Extending between slides 17 is a small shaft 24 which may be adjustably secured therein by means of a set screw 25. Fixedly mounted on this shaft is a frame 26, in which is located a plurality of parallel 50 slats 27, preferably of sheet metal. These slats are at a distance apart corresponding to the spacing desired for the cords, and form, together with their frame, what will be hereinafter termed the comb. Also carried in 55 slides 17 is a fluted roll 28 which serves to

press the cords firmly against the sheet of rubber 14 on the calender roll. The grooves in this roll receive the cords and preserve the spacing given by the comb. It will be seen that by adjusting the position of slides 17, as 70 described above, the roll 28 may be forced against the lower calender roll with any desired degree of pressure.

Carried by the shelf 15 and extending 75 transversely of the machine for substantially the same distance as the comb, is a receptacle 29 adapted to contain the solvent, and having at its upper side an aperture to receive a wick 30, which draws the solvent 80 out of the receptacle by capillary attraction. 85 This wick may be made of any suitable material, such as felt or cotton. Adjacent the top of the wick, and carried either by the frames 10 or by the receptacle 29, are guide members or rollers 31 which serve to 90 guide the cords over the top of the wick. The cords, denoted by 32, are fed from a creel 33 shown diagrammatically in Fig. 1.

The compound fabric of cords and rubber 95 may be wound up on a reel 34 which is conveniently mounted in oblique slots 35 in brackets 36, secured to the side frames. This permits the reel to be frictionally rotated by the lower calender roll, and to move away 100 from the calender roll as the diameter of the reel increases.

The operation of the device described above is as follows—

The cords 32, being led from the creel over 100 guides 31, pass over the wick 30, and are impregnated thereby with the solvent, with which receptacle 29 is kept filled. The cords then pass through comb 27, which locates them in the proper spaced relation, and over roll 28, each cord being received in one of the 105 grooves of this roll. As will be seen from Fig. 4, the cords are preferably slightly spaced, the grooves in roller 28 maintaining them in this position, and are pressed thoroughly into the rubber sheet 14, which penetrates the spaces between the cords as shown in this figure. The solvent which the cords have received from the wick reacts with the rubber and causes the latter to permeate the 110 fibrous material of the cords themselves, insuring a very firm adhesion between the 115 cords and the rubber.

By the procedure outlined above the cords are coated on but one side with rubber. This 120 gives a fabric with sufficient body to enable it being given a coating on the opposite side by any of the usual means for coating ordinary fabric. For example, the fabric from a filled reel 34 may be passed through a three roll calender of the usual type thus receiving a coating on the previously untreated side. If desired, however, the arrangement shown diagrammatically in Fig. 5 may be used. In this case, the fabric 37, prepared as described 125 above, may be passed directly between the 130

rolls 38 and 39 of a three roll calender. This calender has a roll 40 between which and the roll 39 39 a bank of rubber 41 is worked out into a thin sheet 42, which is pressed into contact with the uncoated side of fabric 37 by the rolls 38 and 39. The compound fabric 43 resulting from this procedure and which is shown in section in Fig. 6, may be delivered or rolled up in any suitable way. 10 In Fig. 6, the compound fabric is shown as if it were composed of two distinct layers of rubber, but it will be understood that the layers of uncured stock are inseparably and integrally united as soon as they are pressed together. This method of enclosing the cords between two layers of rubber has the advantage over that first described of applying the second coating of rubber before the solvent has had time to dry out of the 20 cords. The same close cohesion is thus secured between the cords and the second coating of rubber as was the case with the first coating.

Care should be taken that a sufficient 25 width should be given to the wick 30 so that the fabric may be thoroughly coated with the solvent, and the speed of the cords and the distance of travel between the wick and roll 28 should be so regulated that the solvent 30 will have an opportunity to thoroughly permeate the cords.

While I have described both method and apparatus with particular and detailed reference to the manufacture of a cord fabric having an appreciable spacing between the cords, my invention is not limited to such a fabric. The method is equally applicable in its broader aspect to cord fabric, with the cords either adjacent or spaced, thread fabric, or ordinary woven fabric. The apparatus can be readily adapted for use with either thread fabric or woven fabric by merely omitting the comb, and to cord fabric having adjacent cords by decreasing the 45 spacing of the slats of the comb and the grooves in roll 28. In view particularly of this, I do not consider myself limited to the exact structure or procedure shown or described, and have set forth what I believe to 50 be my invention in the appended claims.

I claim—

1. The method of making cord fabric consisting in applying a rubber solvent to a plurality of cords, pressing the cords against one surface of a sheet of uncured rubber, and pressing a second sheet of uncured rubber against the uncoated side of the cords. 55

2. An apparatus for forming a weftless sheet of rubberized fabric comprising a calender to apply a skim coat of rubber, means adjacent the calender for treating the cords with a cord penetrating material to bind the skim coat to the cords, and cord guiding and holding means adjacent the calender to 60 maintain the cords in the desired parallel re-

lation as they join the skim coat of rubber.

3. In a device of the class described, a receptacle adapted to contain a solvent of rubber, a wick dipping into the solvent in said receptacle and adapted to draw the solvent by capillary attraction therefrom, means to guide fibrous material into contact with the wick, and means to press the material against a sheet of rubber. 75

4. In a device of the class described, a receptacle adapted to contain a solvent of rubber, a wick dipping into the solvent in said receptacle and adapted to draw the solvent by capillary attraction therefrom, means to guide fibrous material into contact 80 with the wick, a plurality of calender rolls between which a sheet of rubber is formed, and a roll for pressing the material against the sheet of rubber on one of the calender rolls. 85

5. The method of forming weftless cord fabric which consists in treating separated parallel cords with a liquid material for binding a skim coat to the cords, maintaining the cords in separated parallel condition 90 until the skim coat is applied, and applying the skim coat on and between the cords to permanently bond them in separated parallel condition. 95

6. In a device of the class described, means 100 for guiding a plurality of parallel cords, a receptacle adapted to contain a solvent of rubber, a wick dipping into the solvent in said receptacle and adapted to draw the solvent therefrom by capillary attraction, said wick being located with a surface adjacent the path of the travel of the cords, whereby the solvent is applied to the cords, and means to press the cords against a sheet of rubber. 105

7. In a device of the class described, means 110 for guiding a plurality of parallel cords, means for impregnating the cords with a solvent of rubber, a plurality of calender rolls between which a sheet of rubber is formed, and a grooved roll constructed and arranged to press the cords against the sheet of rubber on one of the calender rolls. 115

8. In a device of the class described, a receptacle adapted to contain a solvent of rubber, a wick dipping into the solvent in said receptacle and adapted to draw the solvent by capillary attraction therefrom, means for guiding a plurality of parallel cords in contact with the wick, a plurality of calender rolls between which a sheet of rubber is formed, and a grooved roll constructed and arranged to press the cords against the sheet of rubber on one of the calender rolls. 120

9. An apparatus for forming weftless cord fabric comprising means for treating cords with a liquid operative to increase their affinity for rubber, means for arranging the cords in spaced and separated parallel relation and while so arranged pressing 125 130

- them against a previously formed sheet of rubber, and means for pressing a second sheet of rubber against the opposite side of the sheet of cords, whereby the rubber sheets are caused to adhere to the cords and to unite with each other between the cords.
10. In a device of the class described, a receptacle adapted to contain a solvent of rubber, a wick dipping into the solvent in said receptacle and adapted to draw the solvent by capillary attraction therefrom, means for guiding a plurality of cords in contact with the wick, means to locate the cords in spaced parallel relation, and means 15 to press the cords so located against a sheet of rubber.
11. In a device of the class described, means for impregnating a plurality of cords with a solvent of rubber, means to locate the cords in spaced parallel relation, a plurality of calender rolls between which a sheet of rubber is formed, and a grooved roll constructed and arranged to maintain the cords in such relation and to press them against 25 a sheet of rubber on one of the calender rolls.
12. In a device of the class described, a receptacle adapted to contain a solvent of rubber, a wick dipping into the solvent in said receptacle and adapted to draw the solvent therefrom by capillary attraction, means for guiding a plurality of cords in contact with the wick, means to locate the cords in spaced parallel relation, a plurality 30 of calender rolls between which a sheet of rubber is formed, and a grooved roll constructed and arranged to maintain the cords in such relation and to press them against a sheet of rubber on one of the calender rolls.
13. In a device of the class described, means to impregnate fibrous material with a solvent of rubber, means to press one side of said material into contact with a sheet of rubber, and means to press the other side of said material into contact with a second sheet of rubber.
14. In a device of the class described, means to impregnate a plurality of parallel cords with a solvent of rubber, means to press the cords against a sheet of rubber, and means to press the uncoated side of the fabric so formed against a second sheet of rubber.
15. In a device of the class described, means to impregnate a plurality of cords with a solvent of rubber, means to locate the cords in spaced parallel relation, means to press the cords so located against a sheet of rubber, and means to press the uncoated side 55 of the fabric so formed against a second sheet of rubber.
16. The method of uniting rubber and fibrous material consisting in applying to the fibrous material a rubber solvent consisting of benzol with from one to ten per cent of resin added, and pressing the rubber firmly into contact with the fibrous material.
17. An apparatus for forming weftless 70 cord fabric comprising calendering means for forming a sheet of rubber, means for arranging the cords in spaced parallel relation, means for pressing the cords while in such arrangement against the sheet so that 75 the rubber penetrates at least partially between the cords while leaving a smooth surface skim coat of rubber, calendering means for forming a second sheet of rubber, and means for pressing said second sheet against 80 the side of the cords not covered by the first sheet, whereby the two rubber sheets are caused to adhere to each other between the cords and a "fabric" is produced having smooth outer rubber surfaces and embedded 85 spaced parallel cords.
18. An apparatus for forming weftless cord fabric comprising means for working rubber into sheet form and for supporting the sheet so produced, a supply for a series 90 of strands, and mechanism adapted to present the strands to the rubber in parallel relation, said mechanism comprising a grooved roller positioned so that the strands pass over its surface and into contact with the 95 rubber sheet and a device positioned between the grooved roller and the supply for arranging the strands in parallel relation and presenting the strands to the grooved roller in proper relation to be received by 100 the grooves thereof.

THOMAS MIDGLEY.
